[57] CLAIM

The ornamental design for a basket, as shown and described.

DESCRIPTION

FIG. 1 is a front view of basket showing my new design. The rear elevational view being a mirror image thereof;

FIG. 2 is a left side, elevational view thereof, the right side elevational view being a mirror image thereof;

FIG. 3 is a top perspective view thereof, with the handle broken out for clarity of illustration to show the inside bottom of the basket;

FIG. 4 is a bottom plan view thereof;

FIG. 5 is a fragmentary elevational view taken along line 5—5 of FIG. 1; and,

FIG. 6 is a top plan view thereof, taken along line 6—6 of FIG. 1.

FIG. 1

FIG. 2

FIG. 5
